UNITED STATES PATENT OFFICE.

GEORGE HOLT FRASER, OF NEW YORK, N. Y.

SEPARATOR.

1,165,869.

Specification of Letters Patent.

Patented Dec. 28, 1915.

Original application filed December 29, 1910, Serial No. 599,913. Renewed March 30, 1915, Serial No. 18,128. Divided and this application filed June 29, 1915. Serial No. 37,032.

To all whom it may concern:

Be it known that I, GEORGE HOLT FRASER, a citizen of the United States, residing in the borough of Brooklyn, in the county of 5 Kings, in the city and State of New York, United States of America, have invented certain new and useful Improvements in Separators, of which the following is a specification, being a division of my application No. 599,913, filed December 29, 1910.

This invention relates to devices for separating, sizing, bolting, classifying, treating or collecting, materials by utilizing a 15 fluid current, and aims to provide certain improvements therein.

Heretofore it has been common to distribute material within a feed chamber in which air currents act to draw the fine material into an outer casing, the fines settling in the outer casing and the air returning to the feed chamber, the coarse material falling through the air currents in the feed chamber and discharging from the bottom 25 of the latter.

My invention provides improvements especially applicable to devices of this general character, and in its preferred form it utilizes a non-rotary feed tube and an initial 30 distributor, in conjunction with a plurality of superposed annular distributors successively receiving the material, an annular exhaust chamber for each distributor, a blower for each distributor, an annular discharge 35 passage for the combined exhaust of the several blowers, and a plurality of settling chambers successively receiving the return current and classifying the material in suspension therein, a reverse return passage for 40 each settling chamber, means for separately withdrawing the different products, means for adjusting the currents for the respective distributors, and means for controlling the main current.

45 My invention also includes means for driving the distributor and blower, means for adjusting the non-rotary feed spout, improved bearings and bearing dispositions, and various features of improvement in construction, arrangement and details, all of 50 which will be hereinafter more fully set forth.

The accompanying drawing which shows

one adaptation of my invention is a vertical axial section showing the preferred form 55 of my invention.

Referring to the drawing, A indicates a casing, B the driving mechanism, C the feed hopper, D the distributor, E a feed chamber, F a blower, G the dust chamber, H the return passage, I the coarse outlet, and J the fine outlet. These may be of any usual or suitable construction and arrangement capable of distributing the feed, creating the necessary current, and collecting and 65 discharging the products.

Referring to the drawing, I will now describe in detail the preferred form of my invention in the adaptation therein illustrated.

The casing A has a cylindrical body a, and tapering or conical top and bottom, made in sections, preferably halves, braced and flanged, and adapted to be bolted to the adjoining circumferential sections, and it 70 has as many vertical sections as are desired to give the requisite height, two being shown. These sections are shown as straight and connected by bars b which tend to preserve the cylindrical form of the body 75 and support the internal parts in position. The upper part of the casing consists of a head c which is tapered in the form of a truncated cone and has an annular top d, and a central cavity or depressed portion e. 80 The lower part of the casing consists of a conical bottom f, suspended from the top body a. The body a is suspended from the top d, and the latter is suspended from the bearing frame g.

The driving mechanism shown consists of a driving shaft h carrying fast and loose pulleys i, and geared to the driven parts by bevel gears. This shaft is mounted in bearings in the frame g, which frame is shown 95 as crossing the machine and supported by timbers at each side thereof, and the entire device as shown is suspended from the frame, which has one face coinciding with the diametric parting of the body.

The hopper C is preferably a stationary hopper, adapted to turn in any direction to connect with any source of feed, and preferably having a scalper and a tailing chute, and a screw threaded discharge outlet.

The feeder is preferably a non-rotary feed

pipe J which is preferably vertically adjustable, as by screwing into the hopper outlet, and which leads into the casing and discharges onto a distributor K therein, the speed of feed being determined by vertical adjustment of the pipe, or of the distributor, or of both, as desired.

The distributor is preferably a rotary member, and preferably comprises the disk K and one or more successive distributors, 10 as the rings L and M, which are carried by and revolve with the disk K in the construction shown. Opposite the disk K there is located a baffle ring k receiving the discharge therefrom and deflecting it downwardly toward the ring L, opposite which there is another similar baffle ring l, receiving discharge from the ring L and directing it down onto the ring M, opposite which 15 there is another baffle ring m deflecting the material downwardly toward the return cone O. Opposite each baffle ring there is an annular exhaust passage. These are lettered P Q and R respectively. Collectors n 20 and o converge the material on rings L and M.

The exhaust passages all preferably discharge into the exhaust chamber T, which tapers downwardly and outwardly and directs their combined discharge into the annular passage U, through which it passes to the dust chamber G. As the current descends in and escapes from the passage U the heavier dust may be close to the outer 30 wall, from which it will slide into the chamber G, and the air will be correspondingly cleaned of larger particles. The chamber G has a cylindrical discharge pipe j'. As the air discharges from the passage U into the 35 settling chamber G the returning air is drawn from it by an intake V, of greater superficial area than that of the passage U and immediately adjacent thereto, so that the downward motion of the dust in the 40 discharge from the passage U may have opportunity to throw out much dust centrifugally within the chamber G as the air current reverses to reach the return V. The air in the chamber G cleans itself by the 45 process of settling, and by momentum and precipitation, before escaping through the return V, the area of which relative to the passage U is sufficiently great to so diminish the speed of flow of the return current for the air to largely free itself of large floating 50 particles.

A baffle ring v is preferably disposed above the chamber G to intercept the air as it whirls inwardly and to direct it toward the adjacent cone and meet upward currents there, and a regulating ring or 60 damper W is preferably vertically adjustable within the passage V to control the air of the return and thus regulate its current speed. An annular suspended wall w

constitutes the partition between the passages U and V and serves as the outer wall of the return passage H. The cone X constitutes the inner wall of this passage as well as the inner wall of the succeeding 70 settling chamber O', and has an outlet x.

The air current flowing through the inlet of the return passage V, swings inwardly past the damper W and upwardly over the top edge of the cone X, and then flows 75 eventually through the passage H to the center of the chamber O', from whence it may continue to the distributors, between which it may again be forced through the suction passages by the blower F. In blowing to the passages it must traverse the descending shower of material falling from each distributor to the next, composed of coarse and fine material, from which, as the current passes through, particles fine enough 85 to be floated by it will be carried outward and downward through the blast chamber T, while the coarser material will continue over the distributors to the return cone O and be dropped from the latter into the bottom of the tailings cone S.

Adjustment or regulation of the current as to the different distributors may be obtained by differentiating the blower speed, or otherwise, but is preferably effected from 90 within the chamber E, as by the damper Y controlling the passage y beneath the disk K, the damper Z controlling the passage z beneath the distributor L, and the damper A' controlling the inlet a' beneath the distributor M.

Inclined annular walls b' which provide isolated passages inwardly of the distributors are preferably attached beneath each distributor, and preferably carry blades c' 105 which serve as the blades of the blower F to generate an outward force current within the distributors.

The dampers Y, Z and A' are independently adjustable from below in any suitable 110 manner, as by the rod d' and pipes e' and f' respectively.

The distributor and the blower are carried by and driven from a tubular head B', which is suitably spaced above them to permit the necessary passage for material between the disk K and the head, and which extends upwardly around the pipe J, and is adjustably suspended from the bearings D', and is driven through a gear E' which is preferably driven by a cone pulley F' and belt G' from a reverse cone pulley H' on the shaft h. By shifting the belt the relative speeds of the pulleys F' and H' can be regulated.

Each of the bearings consists of an annular cup i' receiving an annular flange j' so that the bearings run in oil. Each bearing is clamped in a half socket in the frame g so that by removing the clamps the parts can be bodily removed sidewise. The parting 125

faces of these clamps correspond with the diametric parting of the casing, so that by removing a detachable half the interior is accessible.

5 The gears, bearings and collars are inclosed for dust protection, and the upper bearing D' is formed on a frame m' removable carried on the frame g.

10 For classifying or grading the fines my invention preferably provides one or more classifying chambers, between the dust chamber G and the feed chamber E, and a cleaner or dust extractor v" in the return passage H. One auxiliary settling chamber 15 O' is shown, which is preferably concentric of and partly inclosed in the chamber G, and surrounds and partly envelops the chamber E. The discharge from the chamber G slowly flows therefrom toward the 20 inlet o' to the first classifying chamber, and is discharged downwardly in the latter through this contracted annular inlet, so that dust in the current may be precipitated by its velocity and by centrifugal action, 25 as well as by gravity, as the discharge expands within the large part of the chamber O' and the speed diminishes. The exhaust from the chamber O' is slowly withdrawn through a foraminous or interstitial annular 30 cleaner or dust extractor v" surrounding the large outlet P' comprising a part of the return passage H to the cone S and chamber E, or to the succeeding classifying chamber if several are used, where the operation is 35 repeated as often as desired. From the last 40 classifying chamber the discharge is taken through the exhaust passage V and the return passage H and into the chamber E as before explained. Any desired number of 45 these classifying chambers may be interposed between the discharge and the suction chambers and the fineness of product to be collected in each may be determined by the extractor discharging into it or properly 50 proportioning the chambers, or the current speeds, or the superficial area of the inlet and outlet. A separate outlet spout may be provided for each chamber, or the various 55 separations may be combined in one outlet, in which case the auxiliary chambers and cleaners will simply be used as supplemental purifiers of the current returning to the separating chamber.

55 The return passage constitutes a sinuous conduit between the fine chamber G and the distributing chamber E, and when one or more cleaners or extractors are provided in it an intermediate classifying chamber is interposed for each cleaner and these 60 chambers are essentially a part of the return passage, and constitute enlargements or modifications thereof suited to effect the desired current modification best suited to the particular functions of each intermediate chamber. Making these intermediate cham-

bers concentric and annular, and nesting them together between the tailings cone and the conical bottom of the separator attains great compactness, while permitting uniform annular current passages which facilitate uniformity of speed of flow at all sides of any part of any passage or chamber.

70 As thus far described the invention can be used as a current separator alone, but my invention provides for combined mechanical sizings as well as current sizings within the one machine, and this is preferably accomplished by one or more screens beneath the distributing chamber E, receiving the discharge from the return cone O, and grading and sizing it so as to separate 75 out desired sizes before the remaining tailings or fines passing these screens are permitted to fall onto the tailings cone S. Two sizing screens, a coarse inner one Q', and a medium outer one R' each conical and nested together, are shown as yieldingly suspended by springs S' from the return cone O, so as to receive the tailings therefrom. The coarsest material flows down the screen 80 Q' and falls through its outlet to the coarsest outlet q'. Material passing through this screen flows down the screen R' and escapes through the medium outlet r', and material passing through the screen R' flows 85 down the cone S to the outlet I. The outlets r' q' and I are connected to their respective cones by a series of conduits or pipes s' passing each within the next, either concentrically as shown, or nested eccentrically so as 90 to give the greatest external passageway at the lower side if desired. In this manner 95 three mechanical gradings are effected in addition to the current gradings.

100 To agitate the mechanical screens my invention provides a swinging knocker T' which preferably revolves with the distributor and strikes a projection t' on the screen when the latter is depressed, these parts being normally out of coincidence, but being 105 brought into the same path by the depression of the screens either by reason of the weight of material on it if it becomes clogged, or by means of the handle k' when desired. To permit this depression the 110 screens are yieldingly mounted by means of their cylindrical necks l' in the upper ends of their respective pipes s'.

115 The current may be increased or regulated by regulating the dampers in the 120 chamber E or those in the passage H.

125 In operation the material entering the feed pipe will be controlled by its adjustment, the speeds and currents will be regulated to give the desired results and the various products will be separately withdrawn according to classification. One or all of the methods of classification will be used according to particular requirements.

130 It will be understood that the invention is 135

not limited to the particular details of construction, arrangement and combination set forth, as it can be employed in whole or in part according to any modifications.

5. What I claim is:

1. In separators and the like, a casing, means for distributing material therein, and means for causing a current to traverse material distributed therein, in combination with means for successively clarifying said current, comprising a settling chamber, a return conduit, filtering provisions in said conduit, and a second chamber for receiving material from said filtering provisions.
10. 2. In separators and the like, a casing, means for distributing material therein, and means for causing a current to traverse material distributed therein, in combination with means for collecting material in suspension in said current comprising a dust chamber, a return conduit and a foraminous extractor in said conduit.
15. 3. In separators and the like, a casing, means for distributing material therein, and means for causing a current to traverse material distributed therein, in combination with means for segregating and separately discharging material in suspension in said current at successive points in its circulation comprising a dust chamber, a return conduit, an extraction chamber, and an interstitial extractor in the path of the returning current and discharging into said extraction chamber.
20. 4. In separators and similar devices, a casing, annular means for distributing material downwardly therein in an annular descending apron, and means for creating a current therein through such material, in combination with annular superposed means successively intercepting such descending material in said casing, and annular current dividing partitions inwardly of and surrounded by such distributing means dividing such current between said intercepting means inwardly of such distribution.
25. 5. In separators and similar devices, the combination with a plurality of superposed annular distributors for material to be separated, of means inwardly of and surrounded by said distributors for causing a current to traverse such material between each distributor independently of the others.
30. 6. In separators and similar devices, the combination with a plurality of superposed annular distributors for material to be separated, of means inwardly of and surrounded by such distributors for creating a current through such material opposite each distributor independently of any current opposite other distributors.
35. 7. In separators and similar devices, the combination with a plurality of superposed annular distributors of unlike diameter for material to be separated, of an independent

current passage for each distributor inwardly thereof and surrounded thereby.

8. In separators and similar devices, the combination with a plurality of superposed annular distributors for material to be separated, of an independent blower for, inwardly of, and surrounded by, each distributor.

9. In separators and similar devices, the combination with a plurality of superposed annular distributors for material to be separated, of a blast blower surrounded by and inwardly of such distributors for causing an outflowing current therethrough.

10. In separators and similar devices, the combination with a plurality of distributors for material to be separated, and blowers surrounded thereby, of isolated blast chambers for each distributor and a common exhaust passage for said blowers.

11. In separators and similar devices, the combination with a plurality of distributors for material to be separated, and a blower, of an annular exhaust passage surrounding said distributors, a reverse return passage inwardly of said exhaust passage, a previous current cleaner in said return passage, and a settling chamber communicating the said passages.

12. In separators and similar devices, a plurality of concentric settling chambers superposed and in successive communication, and an annular foraminous cleaner surrounding and discharging into one of said chambers.

13. In separators and similar devices, a plurality of concentric settling chambers each partially inclosing the next, a return passage leading to said chambers successively, and an interstitial extractor in said passage and discharging into one of said chambers.

14. In separators and similar devices, a non-rotary feed pipe, a revolving feed disk having a tubular shaft surrounding said pipe, one of said parts adjustable relatively to the other, means for driving said disk, means for creating a current through the material falling therefrom, and means for freeing such current from material carried in suspension thereby at successive points comprising a foraminous extracting member and an annular chamber receiving and withdrawing material extracted thereby.

15. In separators and the like, a distributor, a blower, a conical chamber inclosing such blower, an annular passage communicating with said chamber, a settling chamber communicating with said passage, an annular return passage within said first named passage, an annular cleaner in said return passage, and means for taking the current passing said chamber to said distributor.

16. In separators and similar devices, a casing, means for distributing material

- therein, means for causing a current to traverse such material, a discharge chamber receiving such current, and a return passage for such current, in combination with annular upwardly extending filtering provisions surrounding such passage.
17. In separators and similar devices, a casing, means for distributing material therein, means for causing a current to traverse the distributed material, a discharge chamber receiving such current at one side of said material, and a return passage communicating with said chamber and returning such current to the other side of such material, in combination with foraminous upwardly extending filtering means in the path of such current.
18. In separators and similar devices, a casing, means for distributing material therein, means for causing a current to traverse, such material and a damper beneath said distributor for regulating such current inwardly of the apron of distributed material, and a return conduit, comprising an annular passage beneath said distributor and an upwardly extending annular foraminous extractor surrounding said passage.
19. In separators and the like, a casing, means for distributing material therein, means for causing a current to traverse such material, and a discharge chamber for such current, in combination with an annular upwardly extending filtering provision surrounded by said chamber, and a return passage inwardly of said provision and communicating through the latter with said chamber.
20. In separators and the like, a casing, means for distributing material therein, a settling chamber, and passages leading to and from said chamber, in combination with a clarifier between said chamber and one of said passages.
21. In separators and the like, a casing, means for distributing material therein, a settling chamber and passages leading to and from the latter, in combination with an extractor, surrounding the passage leading from said chamber, and a separate chamber for withdrawing material precipitated by said extractor.
22. In separators and the like, a casing, means for distributing material therein, a settling chamber, and passages leading from the latter, in combination with an extractor chamber surrounding the passage leading from said chamber, and cleaning means mounted in said passages and discharging into said extractor chamber.
23. In separators and the like, a distributor, means for causing a current to traverse material distributed thereby to remove floating material therefrom, a wall spaced opposite said distributor, a discharge chamber outwardly of said wall, and a return pas-
- sage communicating with said chamber for returning current from the outer to the inner side of said wall, in combination with upwardly extending interstitial provisions for intercepting floating material in the return current from said chamber.
24. In separators and similar devices, the combination with a casing, means for distributing material therein, a circular screen in said casing and spaced below said distributing means, means to afford a current passage above said screen, a blower below said distributor and inwardly of said screen for causing a current to traverse distributed material above said screen, and means affording a return passage for such current communicating between the passage above said screen and returning the current within said screen, and separate outlets for coarse and fine materials.
25. In combination, means causing a current to traverse material to be screened, a circular screen receiving such material, a distributor spaced above said screen to afford a passage above the latter for such current, a revolving part carrying strikers within said screen, and internal provisions carried by said screen for receiving the impact of said strikers for vibrating said screen.
26. In combination, means causing a current to traverse material to be screened, a circular screen receiving such material and affording a current passage above its upper edge, a revolving striker for agitating said screen, means carried by said screen for receiving the impact of said striker, said striker and means normally out of coincidence and the one movable relatively to the other to swing them into engagement, and means providing a current inlet to said screen.
27. In combination, means causing a current to traverse material to be screened, a conical screen affording a current passage above it and receiving such material, means affording an annular return passage for such current communicating with said passage above said screen, and cleaning means in said return passage for cleaning such current.
28. In combination, means for distributing material in an annular descending envelop, a circular screen resiliently mounted below and spaced apart from said distributing means to afford a current passage between it and the latter, a revolving blower inwardly of said screen for causing a current to flow outwardly through such material, and means for jarring said screen.
29. In combination, means for distributing material to be screened, a wire mesh screen below and spaced apart from such distributing means to afford a current passage above said screen, means for causing a

current to traverse such material to float out fine material therefrom above said screen, and means for causing a current to traverse the meshes of said screen in opposition to the passage therethrough of material screened thereby.

30. In combination, means for distributing material to be screened, an inclined screen below and spaced apart therefrom to afford a current passage above it, means for causing a fluid current to traverse such ma-

terial through said passage, and means for causing an upwardly flowing fluid current to traverse the meshes of said screen.

In witness whereof, I have hereunto ¹⁵ signed my name in the presence of two subscribing witnesses.

GEORGE HOLT FRASER.
